UNITED STATES PATENT OFFICE

WILLIAM S. GRAHAM, OF CANTON, ILLINOIS, ASSIGNOR TO INTERNATIONAL HARVESTER COMPANY, A CORPORATION OF NEW JERSEY

TILLAGE DISK

Application filed June 8, 1931. Serial No. 542,770.

This invention relates to tillage tools and more particularly to the construction of tillage disks of the skeleton or open type.

Disks of the type stated are adapted to be used on agricultural machines for tillage purposes generally and are commonly used in pairs as covering disks on lister planters. It has heretofore been the practice to construct such disks of assembled parts, as, for instance, the hub, spokes, and rim, which are riveted or otherwise secured together. The main purpose of this invention is to do away with the cumbersome and expensive structure heretofore used and provide a one-piece skeleton disk having the strength and rigidity of the older structures while being of less weight and capable of production at less cost.

A preferred embodiment of the invention is illustrated in the accompanying drawings, wherein—

Figure 1 is a face or front view of the one-piece skeleton disk of this invention;

Figure 2 is a rear or back view of the same; Figure 3 is an enlarged cross section on the line 3—3, Figure 2;

Figure 4 is a cross section of the hub portion of the disk on the line 4—4, Figure 2;

Figure 5 is a cross section of a spoke on the line 5—5, Figure 2; and

Figure 6 is an enlarged detail sectional view through the disk rim where the spokes merge therewith.

The disk structure here disclosed is formed from a single piece of sheet metal, preferably steel, by any preferred method, as by pressing a disk blank into form and then cutting out the mettle between the spokes to provide a wheel-like or open concavo-convex disk of the form illustrated in Figures 1 and 2.

The disk as a whole is preferably of the usual concavo-convex type and its structure consists of a hub portion having a flat center 10 provided with a central opening for reception of a shaft or spindle and with suitable rivet or bolt holes, as shown, for securing the disk to the flange of a bearing sleeve. The flat central portion 10 of the hub is preferably offset inwardly or towards the concave side 50 of the disk, as best seen in Figure 3, and is

surrounded by a dished annular portion 11 in which the metal is bent into arcuate form in cross section. The spokes 12, here shown as four diametrically disposed spokes, are also of dished or arcuate form in cross section and extend from the annular dished portion 11 of the hub. These spokes merge at their outer ends into a rim 13, the periphery of which is beveled or sharpened, as at 14. In the preferred form illustrated the spokes are curved radially in the direction of the axis of the disk and the rim is continued on the arc of curvature of the spokes, thereby disposing the radial diameter or surface of the soil engaging rim of the disk at an obtuse angle to the axis. At the junction of the spokes with the rim the spokes are widened or flared, opposite webs of metal 15 being left to strengthen the structure at this point.

A disk of the construction described will be light, but rigid, as the arcuate formations in the hub and spokes reenforce the disk where desirable for resistance to the bending stresses to which the disk is subjected while in use. Moreover, the absence of rivet or bolt heads, as required in assembled structures, makes the disk less likely to pick up trash in the field.

The particular disk formation described as the preferred form of the invention is obviously capable of modification without departure from the scope of the invention as defined in the following claim.

What is claimed is:

A concavo-convex skeleton tillage disk 55 consisting of an integral metal structure formed with a central portion provided with a shaft receiving opening, a flat annular portion immediately surrounding said opening, an annular portion of arcuate cross section 95 surrounding said flattened portion, spokes of arcuate cross section radiating from said arcuate annular portion, and a peripheral rim into which said spokes merge, the spokes being flared at their junction with the rim. 95

In testimony whereof I affix my signature.

WILLIAM S. GRAHAM.
